UNITED STATES PATENT OFFICE

HARRY HARPER, OF MINNEAPOLIS, MINNESOTA

DESIGN FOR A COFFEE URN

Application filed November 26, 1930. Serial No. 37,792. Term of patent 14 years.

To all whom it may concern:

Be it known that I, HARRY HARPER, a citizen of the United States, residing at Minneapolis, in the county of Hennepin and State of Minnesota, have invented a new, original, and ornamental Design for Coffee Urns, of which the following is a specification, reference being had to the accompanying drawing, forming part thereof.

The figure is a perspective view of a coffee urn showing my new design.

The coffee urn shown in the drawing is of octagonal shape and the four sides not shown are perfectly plain. The cup and saucer are secured permanently to the top of the urn.

I claim:

The ornamental design for a coffee urn, as shown and described.

Minneapolis, Minnesota, November 24, 1930.

HARRY HARPER.
